UNITED STATES PATENT OFFICE.

FRED HIRSH, OF NEW YORK, N. Y., ASSIGNOR TO ADJUSTA COMPANY, OF NEW YORK, N. Y., A CORPORATION OF NEW YORK.

SLIDE BUCKLE.

Application filed February 2, 1925. Serial No. 6,244.

The invention relates to a buckle or slide of the slotted metallic plate type, for the adjustable attachment of a strap to another part of the same strap or to a second strap 5 or other article; and the primary object thereof is to provide a simple, cheap and otherwise satisfactory closure for the legs of boys', golfers' and other knickerbockers.

For a long period of time knickerbockers, 10 or knee pants, were worn only by boys. In recent years they have become more and more popular for golf and other sports. But the great bulk of the demand is still for boys' ready-made knickerbockers, and the 15 supply of these garments, to the retail trade throughout the country, is in the hands of manufacturers with whom the question of each item of cost is of prime importance.

The cuffs, or simple bands, with which the 20 legs of the knickerbockers are finished at the bottom have for their closure been at different times provided with buttons and a great variety of buckles, all more or less satisfactory. For made-to-order garments buttons 25 may be satisfactorily used, but no adjustment in size is possible except by the resetting of the buttons. Hence the demand for buckles with adjustable hold. The early buckles were complicated, requiring a mechanic for their assembly, and therefore expensive. Later there was produced a buckle 30 which was fastened to the band by sharp prongs clinched at the back after piercing the cloth and was provided with teeth to hold the strap end, and this buckle was used for years and by the millions although objectionable because, being made of iron or tin-plate, the prongs would rust and tear out of the cloth and sometimes injure the legs and 35 because it was difficult to use them for any length of time without tearing or wearing out the strap on the teeth. Owing to their objectionable features, however, buckles were at last condemned and buttons were again 40 resorted to almost exclusively for the closure. As a final development, there has come the slide buckle—a slotted plate with a row of teeth along the edge of its outer bar, through which the strap end is threaded and which, 45 in the cheaper grades of knickerbockers, is sewed directly upon the band or cuff or, in the form most approved for the higher grades, is attached thereto by a tape looped around the middle bar either permanently, 50 by sewing down both ends of the tape or, re-

movably, by sewing down one end only and providing a button for the other end. The teeth of this buckle are as objectionable as before. Moreover, the tape attachment is not only expensive but allows the buckle to 60 shift thereon and pull around to one side, while, when sewed on by machine, the threads stretch and the buckle shifts and soon pulls off and, if lost, cannot be replaced since it is practically impossible to purchase 65 a new buckle.

My improved buckle consists of a flat slotted plate which is riveted directly to the bottom band or cuff of the knickerbockers or other part by rivets, or eyelets, provided 70 at the back with large heads or washers, all preferably of a non-corrosive metal or alloy. I thus provide a buckle which can be supplied at low cost and can be cheaply attached, is securely held in place, and cannot 75 be pulled off—a buckle, moreover, which is capable of withstanding the high pressures of the machines used to press ready-made clothing and the wringing rolls of laundries. In its preferred form, the buckle may also, 80 if desired, be either sewed on or attached by a looped tape, or may be used as a simple slide to adjustably secure together the two ends of a strap both of which are threaded through its slots and held therein, and in 85 place of the usual row of teeth the inner edge of both of its outer bars are upset to provide inturned lips against which the strap end is pressed by the cuff or part to which the buckle is attached and so held securely 90 without slipping.

The invention will be understood by reference to the accompanying drawings, in which—

Figure 1 is a plan view illustrating my 95 new buckle in its preferred form and as applied to the bottom cuff of a pair of knickerbockers; Fig. 2 is a section on the line 2—2 of Fig. 1; Fig. 3 is a perspective view of the back of a modified form of the buckle 100 and of the washers used therewith; and Fig. 4 is a sectional view showing this last buckle and the cuff or other piece to which it is attached.

Referring to Figs. 1 and 2, the buckle here 105 shown consists of a flat plate 5 which is pierced to provide a plurality of transverse bars and intermediate slots, the extended inner edge of the outer bars being upset to form inturned lips 6. The slot in its mid- 110

dle bar, which permits of the buckle being used as a strap fastener or in any of the ways in which an ordinary slide buckle provided with three slots can be used, is slightly 5 enlarged at or near its ends, at 7 7, in order to admit and at the same time prevent any shifting of the buckle with respect to the shanks of the tubular rivets or eyelets 8 8 by which the buckle is, or may be, attached 10 to the cuff 10 of the knickerbockers. The eyelets are provided at the back of the cuff with heads 9 9 large enough to prevent their pulling out. When the strap end 11 is threaded through the buckle and drawn 15 tight, the cuff will press it against the lips of the buckle and so provide a secure closure.

The buckle can be attached by an inexperienced person with the aid of a simple eyeletting machine. It costs less than a 20 buckle sewed on upon a sewing machine, and when once fastened in place cannot pull off or shift. Furthermore, the buckle without change is capable of being used in a variety of ways as stated.

25 In the modification illustrated in Figs. 3 and 4, the lips 16 of the buckle 15 are provided with blunt teeth and the tubular rivets 17 are drawn out from the middle bar 18. This may be done when the buckle is made

of copper, brass, aluminum or similar metal. 29 In attaching this buckle to a cuff or other part 20, the rivets are headed at the back over washers 19 to prevent their pulling out.

The buckle may be further modified in its details within the scope of the appended 35 claims.

What I claim as new, and desire to secure by Letters Patent, is—

1. A buckle of the type described which comprises a body pierced to provide four 40 transverse bars and three intermediate slots, the middle slot being enlarged adjacent each of its ends.

2. A buckle of the type described which comprises a body pierced to provide four 45 transverse bars and three intermediate slots, the two outer bars having inturned lips along their inner edges and the middle slot having an enlargement at each of its ends.

3. A buckle of the type described comprising a body pierced to form a plurality of transverse bars and intermediate slots, the inner edges of the two outer bars being notched and upset to provide inturned lips with blunt teeth, and, as means for its attachment, two rivets fixed in transverse spaced relationship centrally thereof. 55
